By Albert Schell
Attorney.

UNITED STATES PATENT OFFICE

JACOB T. LANDGRAF, OF MACOMB, ILLINOIS, ASSIGNOR TO AMERICAN STEEL
PRODUCTS CO., OF MACOMB, ILLINOIS, A CORPORATION OF ILLINOIS

THERMOSTATIC OIL-CONTROL VALVE

Application filed October 8, 1928. Serial No. 310,937.

My invention relates to thermally responsive valves for controlling a flow of liquid, its general objects being those of providing an easily adjusted and non-clogging valve which will afford a tight shut-off without sticking, which will not permit an overstraining of its parts, and which will permit a ready inspection and replacing of the thermally responsive actuating member.

In its immediate commercial application, my thermostatic valve is particularly suitable for automatically controlling the supply of liquid fuel to a burner—as for example, to the burner of an oil-consuming brooder—and my invention aims to overcome many of the difficulties encountered with automatic control valves heretofore employed in connection with such oil burners. More particularly, my invention aims to provide a thermostatic valve having these desirable characteristics:

(1) Intensifying the closing pressure through a lever, so as to insure a firm closure in spite of the pressure under which the oil or other liquid is supplied.

(2) An enclosed and easily assembled leverage arrangement for this purpose.

(3) An effective housing of this lever mechanism against dust.

(4) A positive opening of the valve when the thermally expansible member is cool, so as to prevent its sticking.

(5) An exposed mounting of the thermally expansible member and of the adjustment for controlling the temperature at which the valve closes.

(6) A simple, accessible and adjustable stop for limiting the movement of the valve member in both directions.

(7) A disposition of the valve parts whereby the flow of liquid will flush any solid particles off the enclosed portions of the mechanism and out of the valve casing.

(8) Convenient inspection of the normally housed lever mechanism.

Still further and also more detailed objects will appear from the following specification and from the accompanying drawings, in which

Fig. 1 is a side elevation of a thermostatic

oil valve embodying my invention, taken from the left side of Fig. 2.

Fig. 2 is an enlarged central and vertical section through the same, with the parts in their normal position for permitting the flow of oil through the valve casing.

Fig. 3 is a horizontal section taken along the line 3—3 of Fig. 1.

Fig. 4 is a fragmentary vertical section, taken along the line 4—4 of Fig. 2.

Fig. 5 is a perspective view of the lever of the valve.

Fig. 6 is a reduced perspective view of the stop bracket.

In the illustrated embodiment, my thermostatic valve has as its body a casing 1 of inverted L shape with an inlet opening 2 at its top and an outlet 3 at its bottom. Threaded into the inlet opening is a nipple 4 to which the oil supply pipe 5 is attached, and this nipple has a medial portion of its bore contracted to afford a tapering seat 6 through which the corresponding tapered tip of the valve stem 7 projects upwardly. This valve stem (or closure member) has a lower portion extending through a vertical perforation 8 in a lever 9, which lever is pivoted by a screw 10 to a pivoting arm 11 projecting from one side of the valve casing toward the opposite side of the casing. The lever 9 has a pair of notches 9A in its upper face, which notches afford seats for a pin 12 which extends transversely through the valve stem 7, and a light compression spring 13 is interposed between the pin 12 and the shoulder 14 afforded by the contraction of the bore of the inlet.

Extending upwardly and slidably into the horizontal arm of the inverted L-shaped casing through a bore 15 is a plunger 16, while an exterior bracket arm 17 projects from a lower portion of the casing and is intercepted by the axis of the plunger 16. Threaded upwardly through this bracket arm 17 is an adjusting screw 18 which desirably is fitted with a locknut 19. This adjusting screw supports a thermally expansible member 20, here shown as a double-decked or twin thermostatic wafer which may contain a small amount of ether. This thermally expansible member supports the plunger 16, desir-

ably through a compression spring 21 which can yield in case the expansion of the member 20 distorts its upper face out of axial alignment with the plunger.

With the parts thus arranged and with the plunger of such a length that the free end portion of the lever 9 rests on the upper end of the plunger, the weight of the lever continually tends to swing the lever downward and the upper spring 13 positively causes the valve stem 7 to follow the lever. Consequently, with a suitable adjustment of the adjusting screw 18, the parts are normally in the positions shown in Fig. 2 when the thermostatic wafers 20 are cool; namely, with the valve stem 7 depressed so as to permit oil to flow past its tapering tip into the valve casing 1 and out through the feed pipe 21.

When the temperature around the wafers rises sufficiently to vaporize their ether content, the resulting internal pressure expands the wafers and raises the plunger 16, thereby raising the lever and the valve stem. During this action, the upper spring 13 resists the raising of the lever and valve stem, until sufficient pressure has built up within the wafers, thus preventing the valve from closing with a slam which might jam the valve stem in its tapering seat. However, even a slow closing of the valve might effect such a jamming with an unduly high pressure exerted by the wafers, since the effective pressure is multiplied at the valve seat through the leverage of my valve mechanism. To avoid this, I provide stop means for limiting the upward movement of the plunger, and I desirably also arrange these stop means so that they will limit the downward movement of the plunger and hence the valve stem.

As a convenient stop arrangement for these purposes, I provide the plunger 16 with a portion 16A of reduced diameter extending slidably through a lateral notch 27 the horizontal arm 23 of an elbow-shaped stop bracket, which bracket has its vertical arm 23A fastened to one end of the valve casing by a screw 24. This screw 24 extends through a vertical slot 25 in the bracket arm 23A, so that the stop bracket can be raised or lowered when the screw 24 is slightly relaxed. With the screw 24 tightened, the plunger 16 can move downward only until the upper face of the stop bracket arm 23 is engaged by the shoulder 16B at the upper end of the contracted plunger portion 16A. Likewise, a companion shoulder 16C at the lower end of this contracted plunger portion is disposed for engaging the bottom of the stop bracket arm 23 to limit the upward movement of the plunger as effected by the expansion of the wafer 20.

However, the grip of the screw 24, while ample for rigidly clamping the stop bracket to resist the weight of the plunger and the action of the light upper spring 13, might

not be ample for positively resisting the upward thrust due to the expansion of the thermostatic wafer or wafers. Hence I desirably supplement the latching effect of the screw 24 by auxiliary means for positively resisting an upward movement of the stop bracket, such as a stop screw 28 threaded upwardly through the stop bracket arm 23 and engaging the bottom of the overhanging casing portion. 75

When my thermostatic valve is in use in its illustrated position, the oil flows downwardly through it and enters the casing through the downwardly flaring valve seat, so that possible impurities in the oil will not tend to clog the valve. Likewise, by providing the outlet at the bottom of the casing and desirably contracting the bore of the lower casing arm toward the outlet (as shown in Fig. 2), I cause any sediment to be flushed out readily. 80

To permit a convenient inserting of the lever 9, I provide the casing with a door 29 at the side toward which the rigid pivoting arm 11 extends, this door being normally held closed by a screw 30. The opening of this door permits a ready inspection of the mechanism and also affords access to the pivoting screw 10, so that the lever and valve stem can be removed and even replaced if desired. Likewise, the nipple 4 can easily be removed and replaced, and the immersion of the lever mechanism in the oil insures its ample lubrication and frictionless operation. The exterior mounting of the adjustable stop bracket, which is shown separately in Fig. 6, permits a convenient adjusting of the position of this bracket, while a retraction of the screw 18 allows a ready removal and replacing of the thermostatic wafer when desired. 95

By using an inverted L-shaped housing (consisting of the casing 1 and the nipple 4 in which the valve seat is formed) and extending the plunger slidably upward into the horizontal portion of this housing, I can readily dispose the lever so as to secure a considerable leverage in a compact construction. And by disposing the outlet at the bottom of the stem of the inverted L-shaped housing, I permit the liquid to drain freely out of the housing when the valve is closed, thereby preventing any impurities from settling in the housing. 110

However, while I have heretofore described my valve as used in a position in which the liquid flows downwardly, I do not wish to be limited in this respect and also do not wish to be limited to the use of my valve with any particular liquid or other fluid. 120

Nor do I wish to be limited as to the direction in which the liquid flows through the valve, since the inlet and outlet connections might be interchanged, nor to the position in which the valve casing is mounted. 125

Neither do I wish to be limited to the details 130

of the construction and arrangement here disclosed, since changes might obviously be made without departing either from the spirit of my invention or from the appended claims.

I claim as my invention:

1. A thermostatic valve comprising a casing having an inlet and an outlet, a valve mechanism movably mounted in the casing and adapted to close the inlet, a plunger extending slidably into the casing and engaging a portion of the valve mechanism, a thermostatic member supported by the casing in alinement with the plunger and engaging the latter, an outer arm on the casing extending across the axis of the plunger, a screw threaded through the arm in alinement with the plunger, and a thermally expansible member interposed between the screw and the plunger.

2. A thermostatic valve comprising a casing having an inlet and an outlet, a valve mechanism within the casing and adapted to close the inlet, the said mechanism including a lever, a stop member mounted on the exterior of the casing, a plunger extending through the stop member into the casing and engaging the lever, a thermally expansible member disposed between the outer end of the plunger and an exterior portion of the casing, the plunger having shoulders disposed for engaging the stop member to limit the movement of the plunger in both directions longitudinally of the plunger.

3. A thermostatic fluid control valve comprising a casing having an inlet and an outlet, a valve member movably disposed within the casing and adapted to close the inlet, a plunger extending slidably into the casing; a lever pivoted within the casing and operatively interposed between the plunger and the valve member, thermally expansible means supported externally of the casing and so disposed with respect to the plunger that a rise in temperature will cause the said means to move the plunger in the inlet closing direction, and a spring associated with the valve member, the spring continuously urging the valve member in its inlet-opening direction and also operating through the lever and plunger to resist expansion of the thermally expansible member.

4. A thermostatic valve as per claim 3, in which the plunger is upright and above the thermally expansible member so that the weight of the plunger also resists expansion of the thermally expansible member.

5. A thermostatic valve as per claim 3, in which the thermally expansible member supports the weight of the plunger and portions of the weights of the lever and the valve member, so that the said weights resist expansion of the thermally expansible member.

6. A thermostatic valve as per claim 3, in combination with stop means mounted on the casing and associated with the plunger for

limiting the movement of the plunger in one direction, the stop means being adjustable in position with respect to the casing longitudinally of the plunger.

7. A thermostatic valve comprising a 70 housing having an inlet and an outlet, and having a valve seat associated with the inlet, a lever pivoted within the housing and extending across the axis of the valve seat, a valve stem actuated by the lever and adapted 75 to close the inlet when the lever moves in one direction; a plunger extending slidably into the casing and having its inner end engaging the lever at a greater distance than the valve stem from the pivot of the lever; and a thermally expansible member supported exteriorly of the housing and associated with the outer end of the lever, the thermally expansible member being arranged so that expansion of the said member moves 80 the plunger inwardly of the casing for causing the lever to move in the aforesaid direction.

8. A thermostatic valve as per claim 7 in combination with a stop member exterior of the housing and through which the plunger extends, the stop member being slidably parallel to the axis of the plunger with respect to the housing, and means for latching the stop member against sliding on the housing; 90 the stop member and the plunger having interengageable portions disposed for limiting the sliding movement of the plunger in both directions.

9. A thermostatic valve as per claim 7, in combination with a stop member exterior of the housing and through which the plunger extends, the stop member being slidably parallel to the axis of the plunger with respect to the housing, and means for latching the stop member against sliding on the housing; 100 the stop member and the plunger having interengageable portions disposed for limiting the sliding movement of the plunger in both directions; and threaded means independent of the latching means and interposed between the stop member and the housing for preventing the stop member from sliding in one direction with respect to the housing.

10. A thermostatic valve comprising an inverted L-shaped housing having an inlet in the top of its horizontal portion and an outlet at the bottom of its stem; the housing also having a valve seat associated with the inlet; a lever pivotally mounted within the horizontal portion of the housing on a horizontal axis and extending across the axis of the valve seat; a valve stem carried by the lever and adapted to engage the valve seat; a plunger extending slidably upward into the said horizontal portion of the housing and having its upper end engaging the bottom of the lever; a thermally expansible member disposed below the plunger and supporting the 115 120 125 130

plunger, and supporting means for supporting the said member from the housing.

11. A thermostatic valve as per claim 10, in which the said supporting means comprise an arm fast upon the housing underhanging the horizontal portion of the housing below the thermally expansible member.

12. A thermostatic valve as per claim 10, in combination with a stop member supported by the horizontal portion of the housing, through which stop member the plunger extends; the plunger having two spaced shoulders each disposed for engaging the stop member to limit the movement of the plunger in opposite directions.

13. A thermostatic valve as per claim 9, in combination with an angle-shaped stop bracket comprising a vertical arm fastened to the free end of the horizontal portion of the housing and a horizontal arm through which the plunger extends, the plunger having spaced shoulders respectively adapted to engage the upper and lower faces of the said horizontal arm for respectively limiting the downward and upward sliding of the plunger.

14. A thermostatic valve comprising a housing having an upper inlet, a valve seat associated with the inlet, and a lower outlet; a lever disposed within the housing and pivoted at one end to the housing, the lever extending across the axis of the valve seat; a plunger extending upwardly into the housing and having its upper end engaging the lever near the other end of the lever to support the lever; a valve closure member supported by a medial portion of the lever and adapted to seat on the valve seat; and thermostatic means supported exteriorly of the housing and supporting the plunger; the housing having a movable portion in one side for affording access to the said lever and closure member.

15. A thermostatic valve comprising an inverted L-shaped housing having an inlet in the top of its horizontal portion and an outlet at the bottom of its shank, the housing also having a valve seat associated with the inlet; a lever pivotally mounted within the horizontal portion of the housing on a horizontal axis and extending across the axis of the valve seat; a valve stem carried by the lever and adapted to engage the valve seat; a plunger extending slidably upward into the said horizontal portion of the housing and having its upper end engaging the bottom of the lever; an arm extending from the housing below the plunger, a screw threaded upwardly through the said arm in alinement with the plunger, and thermally expansible means interposed between the upper end of the screw and the lower end of the plunger.

Signed at Macomb, Illinois, September 29th, 1928.

65 JACOB T. LANDGRAF.
